UNITED STATES PATENT OFFICE.

JOSEPH S. DUNCAN, OF CHICAGO, ILLINOIS, ASSIGNOR TO ADDRESSOGRAPH COMPANY, OF CHICAGO, ILLINOIS, A CORPORATION OF ILLINOIS.

PRINTING-MACHINE.

SPECIFICATION forming part of Letters Patent No. 774,658, dated November 8, 1904.

Application filed February 12, 1904. Serial No. 193,246. (No model.)

To all whom it may concern:

Be it known that I, JOSEPH S. DUNCAN, a citizen of the United States, residing at Chicago, in the county of Cook and State of Illinois, 5 have invented certain new and useful Improvements in Printing-Machines, of which the following is a specification.

This invention relates to printing-machines; and its object is to enable a close imitation of 10 type-written letters in printing circular-letters by printing an autograph signature on the circular-letter in the one printing operation and in a different-colored ink from the text of the letter.

15 The invention also has for its object to provide means which can be readily attached to the platen of a printing-machine for automatically printing a signature or other supplemental matter on a circular-letter, and it has 20 other objects in view, which will appear hereinafter.

In the accompanying drawings I have illustrated one manner of embodying the invention in physical form.

25 Referring to the drawings, Figure 1 shows the invention applied to the platen of a printing-machine, which is illustrated partly in section. Figs. 2 to 5, inclusive, are detail views illustrating several positions of the shifter. 30 Figs. 6 and 7 show the invention in normal position at rest and in printing position, respectively. Fig. 8 is a detail sectional view of the inking-pad-shifting means. Fig. 9 is a detail view showing particularly the stamp- 35 shifter and the spring for returning the stamp to normal position. Fig. 10 is a bottom plan view. Fig. 11 is a top plan view of a portion of the bracket.

I believe that my invention can be applied 40 to a variety of platen printing-machines, and it will be understood, therefore, that I do not limit or restrict the invention to embodiment with a machine of any particular kind. For this reason I have not deemed it necessary to 45 illustrate or describe in detail the construction of a printing-machine, as it appears amply sufficient to properly understand the invention to say that the signature-printing mechanism is attached to a platen 15, which

carries a sheet in the usual manner into printing contact with a form on the bed 16. The platen is mounted on a shaft or studs 17 in the main frame 18 and may be actuated by any suitable means, such as the segment-gears 19 19' on each side of the machine, the segments 19' being carried by arms 20, which are rocked by means of suitable connections with the power-shaft 21 and are connected also with arms 22 on each side of the machine carrying rolls 23 for inking the form of the 60 printing-machine.

The signature-printing device is supported in normal position alongside the platen, Fig. 6, by a bracket 24, which is adjustably secured by bolts 25 to the under side of the 65 platen, Fig. 10. The signature-form, which I will refer to for convenience as the "stamp," 26, is carried by one end of an arm 27, which is pivotally connected by links 28 and 29 to the bracket 24. This arm, which I will call 70 the "stamp-arm," is adapted to be shifted to carry the stamp in the arc of a circle described from the pivot-pin 30 of the link 28 between position at rest alongside of the platen, Fig. 6, and printing position on the 75 platen, Fig. 7. This movement of the stamp-arm is accomplished by means of a shifter 31, which is also mounted on the pivot-pin 30 and is normally held in contact with an arm 32 on the link 28 by a spring 33. An adjustable 80 stop 34, Figs. 2 to 5, may be provided on the shifter to engage the arm 32, so that the shifting movement of the stamp may be properly adjusted and regulated. The shifter is operated by a tripper, which comprises an adjustable arm 35, fastened rigidly on the platen shaft or stud or other part and carrying an antifriction-roller 35', Fig. 1. In Figs. 2 to 5 I have illustrated several positions of the shifter to indicate its operation, and referring 90 thereto, Fig. 2 shows the shifter in the position it occupies when the platen is at rest, as shown in Fig. 1. The tripper is so located and adjusted with reference to the shifter that as the platen moves forward (as indicated by 95 arrows in Figs. 2 and 3) to printing position one side, 36, of the shifter travels against one side of the tripper, and in passing the tripper

the shifter is swung slightly thereby against the tension of spring 33 into the position shown in Fig. 3; but this movement of the shifter is not communicated to any of the other parts and performs no function. On the return movement of the platen, as indicated by arrows in Figs. 4 and 5, the other side, 37, of the shifter engages the tripper, Fig. 4, and as the return movement of the platen continues the shifter travels on the tripper and is finally swung on its pivot to the position shown in Fig. 5 against the tension of the spring 38, Figs. 9, 10, which is attached to link 28 and the bracket 24 and is adapted to return the shifter to its normal position, Fig. 2, as soon as it passes the tripper on the return movement of the platen. It will thus be understood that on the forward movement of the platen the shifter is moved in passing the tripper from the position shown in Fig. 2 to the position shown in Fig. 3 and is returned to the position shown in Fig. 2 after passing the tripper by the spring 33, and it will also be understood that upon the return movement of the platen the shifter travels from its outer end for a distance up toward its pivot and then back again to its outer end on the tripper, as indicated in Figs. 4 and 5, and during this movement the shifter engages the arm 32 and causes the link 28 to swing on its pivot 30 and swing the stamp from position at rest into printing position. This movement of the stamp is made quickly while the platen is returning from printing position, and the operation of feeding sheets to the printing-machine will not in any way be interfered with by the automatically and quickly operating signature-stamp. When the spring 38 pulls the stamp back from printing position to normal position, a pin 39 on the link 28 engages and rides against a spring-arm 40, which may be conveniently supported by the tripper-arm 35. This arm 40 acts as a guide-stop to prevent the printing devices from returning to normal position with a jerk and to allow the stamp and stamp-arm to swing backward easily into normal position. The spring-arm is bent or inclined, Fig. 7, rearwardly from the point where the pin first engages it as the link and other printing devices swing back to position at rest.

The stamp 26, which may consist of any suitable form, is carried by a holder 41, which is fastened in place on the stamp-arm by screws 42 and is adjusted by the screws 43, which pass through the arm and bear upon the holder.

The inking device comprises a pad 44, which is supported in place on the bracket 24 beneath the stamp when the latter is in position at rest, and this pad is adjusted in proper position by the adjusting-screws 45, which operate in the bracket. The inking-pad is held in place on the bracket by a spring 46,

which is attached to the pad and passes through an opening 47 in the top 48 of the bracket and is fastened thereto below the top. It is desirable that the stamp should not engage the pad at the same place each time, and for this reason I provide means for shifting the pad so that the stamp will make contact with a different part of the face of the pad at each operation of the machine. The pad-shifting means comprises a shaft 49, which is journaled in a bearing 50 on the bracket and carries a disk 51, provided with a crank-pin 52, which works in an opening 53 in the under side of the pad, Fig. 8. This crank-shaft is operated to shift the pad by means of a lever 54, which carries a feed-pawl 55, engaging the ratchet 56, mounted on the shaft 49. The lever 54 projects into the path of movement of the stamp-arm, as shown in Fig. 10, and is engaged and operated by the stamp-arm when it moves to carry the stamp into printing position. Whenever the shaft 49 is turned, the inking-pad is shifted on the bracket, and this shifting movement of the pad occurs at each operation of the stamp-arm, so that when the stamp returns to its normal position the pad will be at rest and remain so until the stamp-arm has carried the stamp a given distance to printing position. A spring-arm 57 is arranged to operate at the same time upon the feed-pawl and the lever for returning the lever to normal position, Fig. 10; but any other suitable means for this purpose may be employed. I may also employ a locking-dog 58 to engage and hold the ratchet against reverse movement. It is desirable that the stamp should not lie in actual contact with the pad while the machine is not in operation to avoid unnecessary wear upon the pad and prevent it from becoming misshapen by a constantly-applied pressure. For this reason I provide means to prevent the stamp from contacting with the pad until immediately before the operation of the stamp begins, and this means comprises a yielding stop 59, which is adapted to support the stamp-arm upon its return to normal position and hold the stamp slightly elevated above the pad, Fig. 6. The stamp-arm is held with the pad in this elevated position until the platen has been carried to printing position, at which time the top of the stamp-arm engages a bracket 60 or some other fixed part on the main frame of the machine with sufficient force to overcome the pressure of the yielding stop, so that the stamp will be carried against the pad. I also provide a flat spring-arm 61 on the bracket, Figs. 6, 7, to engage the stamp-arm when the stamp reaches printing position and prevent it from rebounding.

The operation of the signature-printing device will be readily understood from the foregoing description of the construction. The arrangement of the parts is such that the stamp is caused to operate upon the sheet carried by

the platen after the sheet has been printed and on the return movement of the platen to normal position. The stamp is not only carried forward to print upon the sheet, but is 5 carried back to its normal position at rest during this return movement of the platen, and the operation of the stamp is performed quickly, so that it will not interfere in any way with the operation of removing the printed sheet 10 and placing a fresh sheet in position on the platen.

The signature-printing device can be adjusted on the platen and the tripper can be adjusted relative thereto to provide for printing 15 the signature at any desired place on the sheet, and it will be understood that instead of printing a signature the device may be employed for printing any other desired matter, as the stamp can be changed and the parts adjusted 20 as desired.

The device is simple in construction and automatic in operation, and it can be applied to a variety of platen printing-machines.

Of course the stamp may print in a different- 25 colored ink from that employed in printing the text of the letter, and as the stamp can print an autograph signature it will be seen that a complete letter can be printed in very close imitation of a type-written and personally-signed letter.

The platen which carries the sheet to the first printing operation, being the customary printing operation of platen printing-machines, can be oscillated by other means than 35 that disclosed in the drawings; but my invention does not pertain to the platen nor to the means for operating it, but to a printing device carried by the platen, preferably at one side thereof and adapted to be moved in an 40 angular direction with relation to the movement of the platen to print upon the sheet while carried by the platen within the limits of its oscillating movement.

Without limiting myself to the exact construction and arrangement of parts herein 45 shown and described, what I claim, and desire to secure by Letters Patent, is—

1. In a printing-machine, the combination with an oscillating member for carrying a 50 sheet to be printed, of a stamp device carried by said member, and means for operating said device to print upon the sheet while carried by said member.

2. In a printing-machine, the combination with a movable platen for carrying the sheet 55 to be printed into printing position, of a stamp carried by the platen for printing on said sheet.

3. In a printing-machine, the combination with a movable platen for carrying the sheet 60 to be printed into printing position, of a stamp carried by the platen at the side of the sheet, and means for moving said stamp to print on the sheet while carried by the platen.

4. In a printing-machine, the combination 65 with a platen arranged to travel in the arc of a circle and carry a sheet into printing position, of means carried by the platen for again printing on the sheet while carried by the platen between the first printing position and 70 its initial position.

5. In a printing-machine, the combination with a movable platen for carrying the sheet to be printed into printing position, of a stamp carried by the platen at one side of the sheet, 75 and means for moving the stamp to print on the sheet while being carried by the platen from the first printing position to its initial position.

6. In a printing-machine, the combination 80 with a movable platen for carrying the sheet to be printed into printing position, of a stamp carried by the platen at one side of the sheet, and means for moving said stamp at an angle to the movement of the platen for printing on 85 the sheet while carried by the platen.

7. In a printing-machine, the combination with a movable platen for carrying the sheet to be printed into printing position, of a stamp carried by the platen at one side of the sheet, 90 and means for swinging said stamp in the arc of a circle to print upon the sheet while carried by the platen.

8. In a printing-machine, the combination 95 with a platen for carrying the sheet to be printed, of a fixed form for printing on the sheet, a stamp carried by the platen at one side of the sheet, and means for moving the stamp in the arc of a circle to print upon the sheet while carried by the platen between the 100 first printing position and its initial position.

9. In a printing-machine, the combination with a movable platen for carrying the sheet to be printed into printing position, of a stamp, 105 an arm carrying said stamp and pivotally connected to the platen, and means for moving the stamp to print on the sheet while carried by the platen.

10. In a printing-machine, the combination with a platen for carrying the sheet to be 110 printed, of a form for printing on the sheet, a stamp carried by the platen, a shifter connected to said stamp and a tripper adapted to actuate said shifter to cause the stamp to print upon the sheet.

11. In a printing-machine, the combination with a platen for carrying the sheet to be printed of a form for printing on the sheet, a stamp carried by the platen, a shifter connected to the stamp, and a tripper on the machine adapted to be engaged by the shifter to actuate the shifter and move the stamp to print on the sheet while carried by the platen between the limits of its movement.

12. In a printing-machine, the combination 125 with a platen for carrying the sheet to be printed, of a form for printing on the sheet, a stamp adapted to swing in the arc of a circle

at an angle to the movement of the platen to print on the sheet while carried by the platen, and means for retarding the return movement of said stamp to initial position.

5 13. In a printing-machine, the combination with a platen for carrying the sheet to be printed, of a form for printing on the sheet, a stamp carried by the platen, a tripper on the machine for causing the stamp to print upon the sheet, and a guide to regulate the return of the stamp to initial position.

14. In a printing-machine, the combination with a platen for carrying the sheet to be printed, of a form for printing on the sheet, a stamp carried by the platen, a tripper adjustably mounted on the machine adjacent to printing position, and a shifter connected to the stamp and adapted to be operated by said tripper while the platen is on its return movement to cause the stamp to print upon the sheet.

15 15. In a printing-machine, the combination with a platen for carrying the sheet to be printed, of a stamp carried by the platen, a shifter connected to the stamp, a tripper adapted to operate said shifter to cause the stamp to print upon the sheet, and means for retarding the return movement of the stamp.

16. In a printing-machine, the combination with a platen for carrying the sheet to be printed, of a stamp carried by the platen, a tripper, and a shifter connected to the stamp and comprising an arm adapted to be operated by the tripper to operate the stamp.

17. In a printing-machine, the combination with a platen for carrying the sheet to be printed, a stamp, an arm carrying the stamp, a link pivotally connected to the stamp-arm, a tripper, and a shifter comprising an arm adapted to be operated by said tripper to engage said link and operate the stamp.

18. In a printing-machine, the combination with a platen for carrying the sheet to be printed, of a stamp carried by the platen, a shifter connected to the stamp and adapted to move the stamp in the arc of a circle to print upon the sheet, a tripper arranged to operate said shifter, and a spring for returning the stamp to initial position.

19. In a printing-machine, the combination with a platen for carrying the sheet to be printed, of a printing device carried by said platen and adjustably mounted thereon, and means on the machine adjustable relatively to said printing device to operate the same.

20. In a printing-machine, the combination with a platen for carrying the sheet to be printed, of a stamp carried by the platen, an inking-pad, means for moving said stamp to print upon the sheet, and means for preventing the stamp from engaging with the pad until it is about to move into stamping position.

21. In a printing-machine, the combination with a platen for carrying the sheet to be printed, of a stamp carried by the platen, an

inking-pad, means for moving the stamp from the pad to print upon the sheet, means for maintaining the stamp out of contact with the pad, and means for causing the stamp to engage the pad prior to its movement to stamping position.

70 22. In a printing-machine, the combination with a platen for carrying the sheet to be printed, of an inking-pad, a stamp arranged to travel between the pad and stamping position on the platen, means for normally preventing the stamp from engaging the pad, and means for causing the stamp to engage the pad prior to its movement to stamping position.

75 23. In a printing-machine, the combination with a platen for carrying the sheet to be printed, of an inking-pad carried alongside of the platen, a stamp carried by the platen and adapted to swing from normal position above the inking-pad to stamping position on the platen, yielding means for holding the stamp out of contact with the pad, and means for causing the stamp to engage the pad when the platen is moved to printing position.

80 24. In a printing-machine, the combination with a platen for carrying the sheet to be printed, of a printing device carried by said platen, an inking-pad for said printing device, and means for shifting said pad at each operation of the printing device to prevent the printing device engaging the pad at the same place in successive inking operations.

85 25. In a printing-machine, the combination with a platen for carrying the sheet to be printed, of a stamp-arm carried by said platen, a stamp carried by said arm, an inking-pad, and means adapted to be operated by said stamp-arm to shift the pad at each operation of the stamp to prevent the stamp engaging the pad at the same place in successive inking operations.

90 26. In a printing-machine, the combination with a platen for carrying the sheet to be printed, of a stamp-arm, a stamp carried by said arm, an inking-pad, a crank device connected to said inking-pad, and means operated by said stamp-arm for operating said crank device to shift the pad at each operation of the machine.

95 27. In a printing-machine, the combination with a platen for carrying the sheet to be printed, a bracket on said platen, an inking-pad, yielding means for connecting said pad to the bracket, a stamp adapted to engage said pad, and means for shifting the position of the pad on the bracket at each operation of the stamp.

100 28. In a printing-machine, the combination with a platen for carrying the sheet to be printed, of an inking-pad, a crank connected to said pad, a ratchet connected to said crank, a lever for operating the ratchet, a stamp adapted to engage the pad, and an arm con-

nected to said stamp for engaging and operating said lever.

29. In a printing-machine, the combination with a platen for carrying the sheet to be printed, of a bracket on the platen, a shiftable pad guided on said bracket, a stamp, an arm carrying said stamp, and means adapted to be

operated by said arm to shift the pad at each operation of the stamp.

JOSEPH S. DUNCAN.
